UNITED STATES PATENT OFFICE.

ERNEST KOHLER, OF ALAMEDA, CALIFORNIA.

GAME.

1,260,396.

Specification of Letters Patent. Patented Mar. 26, 1918.

Application filed September 1, 1917. Serial No. 189,392.

To all whom it may concern:

Be it known that I, ERNEST KOHLER, a citizen of the United States, residing at Alameda, in the county of Alameda and 5 State of California, have invented certain new and useful Improvements in Games, of which the following is a specification.

This invention relates to certain new and useful improvements in games or puzzles.

10 The primary object of the invention is to provide a game which requires considerable skill on the part of the player and comprehends the employment of a paddle provided with a receiving chamber or pocket, and a 15 number of game pieces adapted to be placed on the paddle one at a time and introduced into the receiving chamber through a suitable opening, the shape of the paddle and game pieces being such as to render this 20 object exceedingly difficult of attainment.

A further object of the invention is to provide a plurality of spherical game pieces adapted to be used in connection with the paddle, and to arrange within the receiving 25 chamber of the paddle a plurality of stops to engage the game pieces as they are deposited therein, these stops preventing the game pieces from rolling about in the chamber and clogging up the opening leading 30 thereto or otherwise interfering with the entrance of the remaining pieces.

With these and other objects in view the invention consists in such details of arrangement, construction and combination of parts 35 as will be hereinafter more fully pointed out in the following description and illustrated in the accompanying drawings, in which drawings:—

Figure 1 is a top plan view of the invention.

Fig. 2 is a longitudinal sectional view of the same, and

Fig. 3 is a bottom plan view.

As stated in the objects, the purpose of 45 the present invention is to provide a game which requires the exercise of considerable skill on the part of the player or players and to this end comprehends in its preferred embodiment the employment of a paddle 50 having a broad flat blade and provided with a pocket or receiving chamber preferably carried by the handle and adapted to receive a number of game pieces. These game pieces are preferably made spherical in form 55 so that they may be rolled about upon the upper surface of the paddle blade and by

skillful manipulation of the paddle introduced into the receiving chamber thereof through a suitable opening. The shape of the paddle and the size of the opening being 60 such as to render exceedingly difficult the attainment of this object, thus requiring a certain amount of skill on the part of the player and adding to the interest and zest of the game.

Referring to the drawings for a more detailed description, the numeral 1 indicates the broad flat blade of the paddle and 2 the handle. At a point near the blade 1 the handle is enlarged laterally to provide the 70 widened surfaces or shoulders 3 thus leaving a narrow strip 4 between these shoulders or surfaces and the blade 1. An opening 5 is formed in this strip and in front of this opening is positioned a stop or abutment 6 which in the present instance consists simply of a screw fastened in the blade and provided with a semi-spherical head. The opening 5 communicates with the forward end of a pocket or receiving chamber 7 located beneath the handle 2, this pocket or chamber being formed by securing an oblong strip 8 to the under side of the handle as shown. The central portion of this strip is removed to provide an elongated 85 opening corresponding in size and shape with an elongated recess 9 formed in the under side of the handle and is adapted to be positioned directly beneath said recess. The side and end pieces of this strip form 90 the side and end walls of the pocket 7 and the lower portion of the pocket is closed by a bottom plate 10, which is provided on its upper surface with a series of notches 11 which notches are adapted to serve as stops 95 to engage the spherical game pieces 12 when the latter are deposited in the chamber. The under face of the blade 1 is beveled adjacent the forward end thereof for a purpose to be hereinafter set forth.

When playing the game five of the game pieces 12 are preferably employed, although this exact number is not essential and these pieces are placed upon the floor, table or other support. The beveled edge of the 105 paddle is then placed directly in front of one of these pieces and a quick forward shove will cause the piece to roll upon the blade. The object then is to manipulate the paddle so as to cause the game piece to roll 110 toward the opening 5 and thence into the chamber 7. Owing to the fact that the

opening 5 is formed in the narrow portion 4 of the paddle and the presence of the stop 6, it will be appreciated that considerable skill is required to roll a game piece along the upper surface of the paddle, around the projection 6 and into the opening 5. When the player has succeeded in placing one of the pieces in the chamber 7 the paddle is tilted to roll the piece to the extreme end of the chamber where it will be engaged by the rearmost of the notches 11 and thus prevented from clogging up the opening 5 and interfering with the entrance of the remaining pieces which when received in the chamber are likewise engaged with the remaining notches 11. Various rules can be promulgated to govern the playing of this game. When only one paddle is in use among a number of players each player is given a turn and the winner is the one who succeeds in depositing the entire number of game pieces in the receiving chamber in the minimum amount of time. When each is provided with a paddle the contestants start at the same time and the winner in this case will be the one who first succeeds in depositing all of the game pieces in the receiving chamber.

From the foregoing it is thought that the use of the invention is clear, but I wish it to be understood that various changes may be resorted to in construction and arrangement providing that the same come within the scope of the appended claims and do not depart from the spirit of the invention.

I claim:—

1. A game, including a paddle provided with widened surfaces and equipped intermediate said surfaces with an opening and

a receiving pocket carried by said paddle 40 and communicating with said opening.

2. A game, including a paddle provided with an opening, an abutment positioned in proximity to said opening, a chamber communicating with said opening, and a plurality of game pieces adapted to be deposited in said chamber through said opening. 45

3. A game, comprising a paddle including a handle enlarged at one end to form a blade and provided adjacent said blade with an 50 opening, an open rectangular frame strip secured to the under face of said handle, and a bottom strip secured beneath said frame strip to provide a receiving chamber communicating with said opening. 55

4. A game, including a paddle provided with a handle and a broad flat blade, said paddle having an opening therein, said handle provided with a pocket communicating with said opening, and a plurality of game 60 pieces adapted to be deposited in said pocket.

5. A game, including a paddle having a handle and a large flat blade, said handle being enlarged laterally to provide a broad flat surface at a point spaced from said blade and provided with an opening positioned intermediate said enlarged surface and blade, a receiving chamber communicating with said opening and a plurality of game pieces adapted to be placed upon the paddle 70 and deposited in said chamber. 65

In testimony whereof I affix my signature in presence of two witnesses.

ERNEST KOHLER.
